UNITED STATES PATENT OFFICE.

JOSEF FIEDLER, OF VIENNA, AUSTRIA-HUNGARY.

RULING OR DRAFTMAN'S PEN.

SPECIFICATION forming part of Letters Patent No. 732,534, dated June 30, 1903.

Application filed October 3, 1902. Serial No. 125,760. No model.

To all whom it may concern:

Be it known that I, JOSEF FIEDLER, scientific-instrument maker, a subject of the Emperor of Austria-Hungary, residing at Nussdorferstrasse 12^a, Vienna IX, Austria-Hungary, have invented a certain new and useful Ruling or Draftsman's Pen; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

This invention consists in certain improvements in ruling or draftsmen's pens having removable point-pieces.

In the annexed drawings, Figures 1 and 2 are views, partly in section, of a ruling-pen with exchangeable point-pieces; and Figs. 3 and 4 are detail views in front elevation and central section, respectively. Figs. 5 and 6 are similar views to Figs. 3 and 4, illustrating a modified form of attachment.

With reference to the drawings, the legs or nibs 1 and 2 are made shorter than usual by an amount equivalent to the length of the point-pieces to be used, and they preferably terminate in blunt or broad extremities. To the said legs or nibs are interchangeably attached point-pieces 3 4, which can be constructed in the manner shown in Figs. 1 to 4—that is to say, their inner or idle ends may be provided with a slot or recess 5, so as to have a fork-like appearance, the object of such slot or recess being to receive the fastening-screws 6 6, which are screwed into the legs or nibs 1 2. A steady-pin 7 is provided for each point-piece and is preferably arranged on the leg or nib so as to enter into a corresponding hole provided in the said point-piece. The latter is removed by simply loosening the set-screw 6 by the aid of a screw-driver 10, which is provided upon the removable handle 9. In the same simple and easy manner a new point-piece may be attached. Considering that the cost price of each point-piece is comparatively low, it is preferable to replace them, when damaged, by new point-

pieces, instead of subjecting the damaged point-pieces to a grinding operation.

Another mode of fastening the point-pieces to the legs or nibs is illustrated in Figs. 5 and 6, in connection with which no tool is required in order to attach and detach the point-pieces. In this instance the attachment and detachment are effected by pressing and turning the point-pieces in a manner similar to that employed when using the so-called "bayonet-closing" devices. The point-piece 3 is in this case also provided with a fork-like extremity 5; but the slot thereof is widened at its inner end into a circular opening. The shank of the bolt 6, by which the point-piece is fastened to the nib, is not completely cylindrical; but the cross-section thereof at the part enclosed within the fork 5 is flattened on one side, as at 11, (or even on two sides,) by removing about one-half of its thickness, so that the outer or narrower part of the fork can slide over the bolt-shank in the direction of the face of the flattened side. The fork of the point-piece can only slide over the bolt 6 when the point-piece is in one position—that is to say, the position indicated in chain-lines in Fig. 5, since it is only when in that position that the width of the fork corresponds to the diminished cross-section of the bolt. When the point-piece is turned in the direction shown by the arrow into its working position, it will be secured against becoming detached, since the larger diameter of the bolt is then arranged transversely to the length of the fork, in the enlarged end thereof. When in its working position, the point-piece is, as hereinbefore described, secured from turning by means of the steady-pin 7. It is obvious that by employing this mode of fastening the point-pieces can be readily cleaned and this can be effected without detaching them entirely by slightly turning said point-pieces—that is to say, without bringing them into the position indicated by the chain-lines in Fig. 5.

What I claim is—

1. In a ruling-pen, the combination of a nib, a removable point-piece therefor having openings one of which is in the form of a longitudinal slot, and projections on the nib

adapted to be received by said openings, said point-piece and one of the projections being adapted to interlock to prevent separation of said point-piece from the nib, substantially as described.

2. In a ruling-pen, the combination of a nib, a removable point-piece therefor having openings one of which is in the form of a longitudinal slot bifurcating the butt-end of the point-piece, and projections on the nib adapted to be received by said openings, said point-piece and one of the projections being adapted to interlock to prevent separation of said point-piece from the nib, substantially as described.

3. In a ruling-pen, the combination of a nib, a removable point-piece therefor, a slot at one end of the point-piece provided with an enlargement at its inner end, a bolt projecting from said nib and having a flattened

shank which passes within the said slot in the said point-piece, and a steady-pin for retaining said point-piece in position, substantially as described.

4. In a ruling-pen, the combination of a nib, a removable point-piece therefor, a slot in said point-piece provided with an enlargement at its inner end, a bolt projecting from said nib and having a flattened shank which passes within the said slot in the said point-piece, and a steady-pin for retaining said point-piece in position, substantially as described.

In testimony that I claim the foregoing I have hereunto set my hand this 18th day of September, 1902.

JOSEF FIEDLER.
